CLAMP GUIDE

John K. van der Schuur, Oakland, Calif.

Application November 26, 1945, Serial No. 630,866

3 Claims. (Cl. 242—117)

1

This invention relates to clamp guides and more particularly to adjustable guides for rope drives for cable reels.

Among the objects of the invention is to facilitate the application of belt driven power to the rotation of cable and similar reels.

Another object is to provide guide means for facilitating the bunching and assembling of wires and strands and tying them into cables or bundles.

A further object is to provide such guides that may be easily and cheaply fabricated in light weight material.

Other objects and advantages will appear as the description progresses. In the specification and the accompanying drawings the invention is disclosed in its preferred form. But it is to be understood that it is not limited to this form because it may be embodied in modifications within the spirit of the invention as defined in the claims following the description.

In the one sheet of drawings:

Fig. 1 is a side elevation diagrammatically illustrating the application of the invention to a cable reel.

Fig. 2 is a similar view of a clamp guide constructed in accordance with this invention.

Fig. 3 is a front elevation of the same.

Fig. 4 shows a modified means for moving the jaws relative to each other.

In detail the structure illustrated in Fig. 2, 30 comprises the fixed jaw 1, having the narrower flat jaw guide 2 welded thereto. The movable jaw 3 has the slot 4 engaging the guide 2.

The bracket 5 is welded to the end of the guide 2 and projects above and below the plane of the guide and limits the lateral movement of the jaw 3.

The spindle 6 is threaded through the bracket 5 that is reinforced at this point by the nut 7 welded to the bracket. The outer end of the spindle has the transverse handle 8 welded thereto. The inner end of the spindle bears against the jaw 3, to adjust it relatively to the fixed jaw 1.

This invention has many uses and is particularly adaptable in providing a peripheral guide for a rope drive applied to cable reels.

Flexible cables such as 9 are wound on cylindrical reels having wide circular ends such as 10. These cables while flexible, are often enclosed within lead sheaths and are heavy and awkward to handle in winding them upon the reels. The cable factories are equipped with power means for rotating the reels in winding new cables. But it often happens in salvaging used cables it is

2

necessary to rotate the reels in field work by hand labor, a tedious and awkward undertaking.

In laying and salvaging submarine cables, or raising them for inspection the same problems are involved. Repair barges and cable ships are equipped with power driven winches available for rotating the cable reels, but heretofore no means has been provided for utilizing such winch power, or it has been complicated and highly specialized.

The present invention is applicable to any cable reel to adapt it to belt drive from any source of rotary power. This invention operates substantially as follows: The clamp guides shown in Fig. 2, are placed around the periphery of the reel end 10, as shown in Fig. 1. The jaws 1 and 3 are straddled over the thickness of the end 10, with the jaw guide 2 resting snugly on the periphery of the reel end. The spindle 6 is then screwed inwardly against the movable jaw 3 until it binds the reel end 10 tightly between the jaws 1, 3.

The upper portions 11, 12, of the jaws and the top of the guide 2, form an open guide to receive the rope or belt drive 13 passing around the periphery of the end 10 within these top guides, which prevent its displacement laterally when power is applied.

The rope drive 13 is then wrapped around the winch head or other source of power 14. The bight of the rope 13 then passes around an idle pulley not shown, that is movable to apply tension to the rope and cause it to be driven by the winch head 14, to rotate the reel, the desired distance to expose the cable 9 for inspection and tests applied in the usual manner.

The invention resides particularly in the structure and mode of operation of the clamp guide and, in combination with the structure with which it cooperates.

These clamp guides may also be applied to suitable interspaced supports to hold the length of cable in a horizontal position for the desired distance. Or they may be similarly aligned to function as guides in holding a number of cables or strands in assembly for convenient tying or wrapping together.

The modification shown in Fig. 4, is the same general structure with the jaw 1, guide 2 having the longitudinal slot 2x therein, forming the divided bracket 5x with the eye bends such as 7x therein. The cam 6x is substituted for the spindle 6, and bears against the movable jaw 3, to force it toward the jaw 1, when the handle 8x is swung downwardly.

Having thus described this invention and its

mode of operation which I claim and desire to secure by Letters Patent is:

1. In combination with a cable reel having a flat circular end; a belt guide having a relatively thin stationary jaw bearing against the inner face of said reel end and projecting beyond said periphery and having a flat jaw guide bearing against said periphery and fixed intermediate the length of said stationary jaw and having its outer end extending angularly and substantially 10 parallel with the plane of said stationary jaw; a movable jaw extending above and below said periphery and having a slot slidable on said jaw guide; and a spindle threaded through the outer end of said jaw guide and bearing against the 15 outer face of said movable jaw.

2. In combination with a cable reel having a flat circular end with a series of removable belt guides interspaced around its periphery, each guide having a stationary relatively thin jaw bearing against the inner face of said reel end and projecting beyond said periphery and having a flat jaw guide fixed intermediate the length of said stationary jaw and lying flat against said periphery and having its outer end extending angularly to the plane of said jaw guide; a movable jaw extending above and below the plane of said periphery in opposed relation to said stationary jaw and having a slot therethrough slid- 25 able on said jaw guide; a spindle threaded through 30 the outer end of said jaw guide and bearing

against said movable jaw, for clamping said opposed jaws against the thickness of said circular reel end; and a driven belt encircling said end and guided between the projecting ends of said jaws, for driving said reel.

5. A clamp guide comprising a fixed jaw having a relatively thin flat jaw guide projecting laterally therefrom and fixed intermediate the length of said jaw; a movable jaw having a transverse slot intermediate its length and slidable upon said jaw guide, the upper portions of said jaws forming a U shape rope guide above said jaw guide and the lower portions of said jaws forming a jaw clamp beneath said jaw guide; and means mounted on the projecting end of said jaw guide for moving said movable jaw relative to said fixed jaw and maintaining an equal width between said jaw portions of said U shape rope guide and said jaw clamp.
